SMOKER'S ARTICLE

Application filed March 5, 1930. Serial No. 433,234.

The present invention relates to smokers' articles and is more particularly directed toward smokers' articles adapted for extinguishing cigars and cigarettes and for cutting off the tips of the cigars.

The present invention contemplates a smoker's article suitable for the above purposes or either of them, so designed that it may form an ornamental article, effective to extinguish cigarettes or cut cigar tips and receive the débris, as well as ashes, butts and other trash.

These objects may readily be accomplished by employing a hollow base having suitable openings for inserting the ignited end of the cigarette to be extinguished or the cigar tip, as the case may be. A movable compressor is mounted inside the upper part of the hollow base and is so arranged that it is normally below the opening or openings in the base. The compressor is connected to an externally accessible device, such as a lever integral with it, for moving the compressor up to squeeze the end of the cigarette to extinguish it. Where the device is to act as a cigar cutter, a blade, such as a razor blade, is carried by the compressor, and suitable provisions are made to care for and dispose of the tip.

The accompanying drawings show, for purposes of illustrating the present invention, two forms in which the invention may be embodied, it being understood that the drawings are illustrative of the invention rather than limiting the same.

In these drawings:

Figure 1 is a perspective view of one form of construction;

Figure 2 is a top plan view of the center part of the base, with parts in section on the line 2—2 of Figure 1;

Figure 3 is a vertical sectional view on the line 3—3 of Figure 2, the normal position of the parts being shown in full lines, and the cutting or snuffing position being shown in dotted lines;

Figure 4 is a sectional view on the line 4—4 of Figure 3, the compressor and blade being shown in the upper position; and

Figure 5 is a broken perspective view to

illustrate a modified form of construction.

The smoker's article herein shown is in the form of a hollow base 10 of stepped or set back configuration and may be made square, round or of any other configuration to form 55 a suitable ornamental body. It may be surmounted by a statuary figure or other ornament 11, or may form a lamp base or a base for a lighter.

As shown in the drawings, the base 10 is 60 square and has vertical side walls 12—12 which extend up to horizontal set backs 13. The set backs 13 have openings or holes 14 to permit cigar ashes, matches or other trash to be passed through into the inside of the 65 hollow base. They may also carry cigar rests, indicated at 15. The hollow base also has vertical side walls above the set backs, as indicated at 16, and a flat top 17 adapted to support the ornamental figure 11. The side 70 walls 16 are provided with openings 18 to permit one to insert the ignited end of a cigarette or the tip of a cigar into the inside of the hollow base.

A movable compressor member 20 is carried within the upper part of the hollow base. This compressor member 20 is integral with a finger piece 21 which extends out through an opening 22 in the rear of the upper part 75 of the hollow base. The inner end of the compressor member is heavier than the finger piece and, hence, it normally hangs down somewhat as indicated in Figure 3. One side of the compressor member 20 has downwardly extending flanges or ears 23 threaded to receive screws 24 by which one may secure a razor blade, indicated at 25. This razor blade extends above the upper surface of the compressor member 20, and, when the finger 80 grip 21 is depressed, this blade passes up by the opening 18 to cut off the end of a cigar which may be inserted through this opening. The top wall 17 is cut back as indicated at 27, to accommodate the cutter blade and allow 85 the complete severing of the cigar tip without interfering with complete compression of the end of a cigarette. When the pressure is released, the plate 20 drops and shakes the ashes off into the bottom of the base.

Figure 4 is a sectional view on the line 4—4 of Figure 3, the compressor and blade being shown in the upper position; and

Figure 5 is a broken perspective view to

In order to facilitate the renewal of blades, the adjacent side wall 16 is provided with openings 28, so that one can remove the screws 24. A sliding bottom 30 is carried across the lower part of the hollow base and acts to close the base.

In the modified form of construction illustrated in Figure 5, the base may be constructed in substantially the same manner as before, and the same reference characters (with a prime added) are employed as in the corresponding parts. Instead, however, of using an oscillatory compressor, this form of construction provides for a vertically movable ring like plunger 31 carried in the upper part of the hollow base. The plunger and pressure receiving surface 32 are sloped as shown so that the ashes may drop away and the compressor be self-cleaning. This plunger has a stem 33 reduced at the lower end, as indicated at 34, and passing through a lever 35. The lever is carried on a suitable stem or stud 36 and extends outwardly and upwardly where it is provided with a button 37 by which it may be operated.

The smokers' articles which have been described are well adapted for the purpose of extinguishing cigarettes and/or cutting off cigar tips. A number of openings 18 are provided so that the ignited cigarette may readily be inserted into the hollow base from any direction. It may either rest on the compressor member or may be held in one hand while the finger grip 21, or the button 37, is pressed down, thereby raising the compressor member and squeezing the ignited end of the cigarette against the top wall of the base. This extinguishes the cigarette immediately, so that it cannot smoulder.

Furthermore, the employment of a hollow base makes it possible to provide a device suitable for this purpose wherein the accumulation of trash is kept in a closed container from which it cannot be blown out by drafts; also there is no possibility of fire from ignited cigarettes which might be dropped in through the holes 14.

It is obvious that the invention may be embodied in many forms and constructions, and I wish it to be understood that the particular forms shown are but two of the many forms. Various modifications and changes being possible, I do not otherwise limit myself in any way with respect thereto.

What is claimed is:

1. A cigarette extinguisher comprising a downwardly opening hollow base having a top wall and side walls, a side wall having an opening near the top wall to permit inserting a cigarette so that the ignited end thereof is underneath the top wall, and a movably mounted compressor normally positioned to permit such insertion and movable to squeeze the end of the cigarette against the lower surface of the top wall.

2. A cigarette extinguisher comprising a downwardly opening hollow base having a top wall and side walls, a side wall having an opening near the top wall to permit inserting a cigarette so that the ignited end thereof is underneath the top wall, and a lever extending through the side wall of the base and having a compressor portion inside the base and operable from outside the base to move the compressor portion toward the lower surface of the top wall of the base to squeeze the end of the cigarette.

3. A cigarette extinguisher comprising a downwardly opening hollow base having a top wall and downwardly extending side walls, the walls having a number of openings adjacent the top wall to permit the insertion of a cigarette through a selected opening so that the lighted end is underneath the top wall, and a pivoted compressor normally below the opening to permit such insertion and movable to squeeze the end of the cigarette against the lower surface of the top wall.

4. A cigarette extinguisher comprising a hollow base closed by a wall extending across the top and having depending side walls one of which is apertured to receive a compressor lever, a compressor lever passing through said aperture and having an externally accessible finger piece and a heavy inner end normally below cigarette receiving openings in the side walls, the lever being pivoted about a horizontal axis sufficiently remote to permit moving the inner end of the compressor lever against the inside of the top wall of the base to squeeze the cigarette against the same and extinguish it.

5. A cigarette extinguisher and cigar cutter comprising a hollow base having apertured side walls adapted to admit a cigarette or cigar tip and a stationary pressure receiving surface above the aperture and within the base, a compressor movably supported by the base and below the aperture and carrying a cutter movable past the opening to sever a cigar tip, the compressor being movable against the pressure receiving surface to extinguish a cigarette.

6. A cigarette extinguisher and cigar cutter comprising a hollow base having apertured side walls adapted to admit a cigarette or cigar tip and a stationary pressure receiving surface above the aperture and within the base, a compressor movably supported by the base and below the aperture and carrying a cutter movable past the opening to sever a cigar tip, the compressor being movable against the pressure receiving surface to extinguish a cigarette, the cutter being in the form of a razor blade and secured to a depending extension of the compressor.

7. A cigarette extinguisher and cigar cutter comprising a hollow base having apertured side walls adapted to admit a cigarette or cigar tip and a stationary pressure receiving

ing surface above the aperture and within the base, a compressor movably supported by the base and below the aperture and carrying a cutter movable past the opening to sever
5 a cigar tip, the compressor being movable against the pressure receiving surface to extinguish a cigarette, there being a recess to accommodate the cutter so that the cigar tip is completely severed, and a cut out in the
10 compressor to permit the severed tip to fall away.

8. A cigarette extinguisher and cigar cutter comprising a hollow base having apertured side walls adapted to admit a cigarette
15 or cigar tip, and a stationary pressure receiving surface above the aperture and within the base, a compressor pivoted in the base and below the aperture and carrying a cutter movable past the opening to shear a cigar
20 tip, the compressor being movable against the pressure receiving surface to extinguish a cigarette.

9. A cigarette extinguisher comprising a hollow base of stepped formation and having one set back, the horizontal part of the set back having holes to admit ashes and rests for cigarettes, the wall of the base above the set back having an opening to permit insertion of the end of a cigarette, a snuffer enclosed within the upper part of the base and normally open to receive the end of the cigarette, and an externally accessible, manually operable device for squeezing the end of the cigarette.

35 10. A cigarette extinguisher comprising a hollow base having an apertured side wall adapted to admit the end of a cigarette and a second aperture in the side wall and spaced from the first aperture, a lever extending through the latter mentioned aperture and having a small finger piece outside the base and a heavy compressor plate inside the base and movable past the first aperture to squeeze the cigarette against the top wall of the base.

45 ANDREW J. FOLEY.
